UNITED STATES PATENT OFFICE

1,944,605

INJECTION ENGINE

Franz Lang, Munich, Germany, assignor to Lan-
ova Aktiengesellschaft, Vaduz, Liechtenstein

Original application December 1, 1930, Serial No.
499,223, and in Germany October 30, 1930.
Divided and this application June 19, 1933.
Serial No. 676,428

Claims. (Cl. 123—32)

My invention relates to a fuel injection internal combustion engine of the type which embodies an air chamber in which fluid is compressed during the compression stroke of the piston and from which the fluid issues during the working stroke of the piston.

This application is a division of my copending application, Serial No. 499,223, filed December 1, 1930, for Fuel injection internal combustion engines.

The instant invention contemplates an improved combustion chamber shape and corresponding locations of the fuel nozzle and air chamber, all to the end of obtaining improved organized turbulence, effective mixing of the charge, better combustion of the charge, and keeping the piston and cylinder clear of combustion residue.

My invention is illustrated in the accompanying drawing, in which

Figure 1 is a vertical axial sectional view of those portions of the engine with which my invention is concerned;

Figure 2 is a horizontal sectional view taken on the plane of the line C—D of Figure 1, looking downwardly; the line A—B of Figure 2 indicates the plane on which the section, Figure 1, is taken;

Figure 3 is a vertical axial sectional view taken on the plane of line E—F of Figure 1; and

Figures 4 and 5 correspond to Figure 2 and show the fluid movements during the compression period and after ignition, respectively.

The drawing shows the cylinder, the piston which reciprocates in the cylinder, the fuel nozzle *a*, the air chamber *b*, the combustion chamber *c*, formed in the head of the cylinder, and the valves *d* and *e*, for the admission of air and the exit of the products of combustion.

It will be noted that the combustion chamber *c* is heart-shaped in plan, of considerably less area than the horizontal section of the cylinder, that the nozzle leads into the combustion chamber at the junction of the lobes thereof, and that the air chamber *b* is located with its orifice leading into the combustion chamber at the apex thereof. Thus, the fuel nozzle and the air chamber are co-axial and lead toward each other on the diametrical line of the cylinder, and spaced apart a distance less than the diameter of the cylinder. The air chamber *b* is formed in a plug, which is inserted in an opening in the cylinder casting, as shown in the drawing.

Upon the compression stroke of the piston, fluid from above the piston is compressed in the cham-

ber *b*, and upon the working stroke of the piston this fluid issues from the chamber at high velocity, the stream of fluid being directed against the opposite combustion chamber wall, at the junction of the lobes, where it splits as indicated in Figure 5, the further movement of the fluid taking place in two opposite directions circumferentially along the walls of the respective lobes of the combustion chamber.

Suitable mechanism is of course provided to cause the nozzle *a* to inject fuel into the combustion chamber at the proper time in the cycle, beginning with the final compression, and to actuate the valves at the proper times.

I claim:

1. In an injection engine, a cylinder and a piston operating therein, a main combustion chamber of approximately heart-shape in plan overlying and opening into the cylinder area, said chamber comprising a constriction and lobes at opposite sides thereof, storage means comprising an air storage chamber opening into the combustion chamber at one side thereof and through a passage disposed substantially normal to the cylinder axis, and fuel injecting means at the opposite side of the combustion chamber and disposed to inject fuel thereinto toward the opening of the storage chamber and substantially normal to the cylinder axis, one of said means being disposed at said constriction and between the lobes of the combustion chamber.

2. In an injection engine, a cylinder and a piston operating therein, a combustion chamber overlying and opening into the cylinder area, said chamber comprising in plan a constriction and lobes at opposite sides thereof, an air storage chamber opening into the combustion chamber at one side of the constriction thereof and through a passage disposed substantially normal to the cylinder axis, and fuel injecting means disposed to inject fuel into the combustion chamber at the opposite side of said constriction and toward the opening of the storage chamber and substantially normal to the cylinder axis.
